UNITED STATES PATENT OFFICE.

JAKOB V. GUDMOND-HOYER, OF MORRIS, NEW YORK.

MECHANISM FOR BORING HOLES IN THE EARTH.

1,139,275.

Specification of Letters Patent.

Patented May 11, 1915.

Original application filed April 9, 1914, Serial No. 830,833. Divided and this application filed August 5, 1914. Serial No. 855,181.

To all whom it may concern:

Be it known that I, JAKOB V. GUDMOND-HOYER, a citizen of the United States, residing at Morris, in the county of Otsego and State of New York, have invented certain new and useful Improvements in Mechanism for Boring Holes in the Earth, of which the following is a specification.

The present invention relates generally to improvements in machines for boring holes in the earth and is particularly adapted for subsoiling apparatus of the type disclosed in my copending application Serial Number 830,833, filed April 9, 1914, of which this application is a division. While the mechanism is especially adapted for boring a hole in the earth in which to deposit the explosive charge for breaking up the soil, the apparatus is susceptible of use for other purposes, as for instance in setting fence posts or planting trees.

In carrying out my invention I preferably mount the whole operating mechanism upon a motor vehicle, the propelling means for said vehicle being employed for actuating a hole boring tool and in conjunction with the apparatus I provide means for automatically arresting movement of the vehicle at predetermined distances so as to enable the holes to be at regular intervals apart. These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a side elevation of an apparatus constructed in accordance with my invention. Fig. 2 is a front elevation of the same. Fig. 3 is an enlarged detail view of the clutch operating mechanism for the hole boring tool employed in the apparatus. Fig. 4 is a horizontal sectional view on the line 4—4 of Fig. 3. Fig. 5 is a detail elevation of the vehicle brake. Fig. 6 is a similar elevation of the automatic means for applying the brake at predetermined points during movement of the vehicle, and Fig. 7 is a horizontal sectional view on the line 7—7 of Fig. 6.

Referring to the drawings and specifically describing my invention the numeral 1 designates a motor vehicle, 2 the motor therefor, 3 the driving shaft operatively

connected through the driving chains 4 to the rear driving wheels 5. It will be understood that any desired design of vehicle may readily be used in carrying out this apparatus, and I do not wish to be strictly confined with respect to the details shown in the accompanying illustrations, it being preferable, however, that the vehicle be of a predetermined length to best carry out the operation, as will be hereinafter more fully disclosed. Arranged at the forward extremity of the vehicle is the boring or drilling mechanism comprising a vertically disposed toothed lifting bar or rack 6, operable by means of a hand wheel 7 located adjacent to the driver's seat 8 and the steering column 9, said wheel being carried by the shaft 10 which has at its outer end the pinion 11 meshing with the lifting bar 6.

Referring particularly to Fig. 3 of the drawings it will be noted that the lower extremity of the bar 6 is loosely connected to the upper extremity of a bit or auger or other suitable drilling tool 12, the connection permitting free rotation of said auger during movement of the same by said lifting bar. The auger is driven by means of the shaft 3" which is geared with the driving shaft 3 having a beveled pinion 13 at its extremity intermeshing with a similar pinion 14 on a vertical shaft 15 supported in arms 16 of the depending frame 17 and the lower end of the shaft 15 carries a gear 18 intermeshing with a relatively sliding gear 19 of the clutch element 20. The upper extremity of said clutch element is preferably frusto-conical in shape and extends into a co-operating clutch element 21 which has an internal lug 21 movable in a groove 22 extending longitudinally of the auger, as clearly shown in Figs. 3 and 4 of the drawings, and the lower end of the element 20 has loose connection with the headed extremity of the lifting lever 23 pivotally mounted at 24 on the frame 17. The opposite end of said lever is connected to a foot lever 25, so that it will be obvious upon depression of the foot lever 25 the clutch element 20 will be raised until it frictionally engages the element 21 operatively connected to the auger 12, thereby communicating rotation imparted to the clutch element 20 by the shaft 3" to said auger. The auger is operated to drill a hole the proper depth by means of the hand wheel 7 which lowers or raises the bar 6. In actual use the holes

in the ground to be operated upon are bored at predetermined distances apart and any suitable means may be employed by which to determine the interval between said holes, 5 as hereinafter described.

Upon the rear extremity of the vehicle, and indicated at 26, is located certain charge firing mechanism which forming no part of the present invention will not be described 10 as said mechanism is comprehended by my copending application hereinbefore mentioned.

With the foregoing in mind, the operator disengages the actuating means for rotating 15 the operating tool and raises said tool clear of the ground. The vehicle is then moved through the instrumentality of its motor to the point where the next hole is to be bored in the earth.

20 As hereinbefore mentioned I preferably employ in conjunction with this apparatus means for automatically bringing the motor vehicle to a stop at predetermined points so as to enable the drilling of the openings 25 in the ground by the auger at regular intervals. Such mechanism preferably consists of a cam wheel 44 mounted upon a shaft 45 journaled in a standard 46 near the forward extremity of the machine, which shaft is 30 driven through the driving chains 47, from the vehicle driven shaft 3, as shown most clearly in Fig. 1 of the drawing. The cam wheel 44 is provided with a grooved periphery as indicated at 48, a portion of said 35 groove, at one side of the wheel, being deeply cut out as indicated at 49 in Fig. 7 of the drawings. Secured to the frame of the vehicle adjacent the cam wheel 44 is an operating lever 50 normally held in the 40 groove 48 of the cam wheel by means of a spring 51, the lower end of said lever being connected to the brake rod 52 passing to the brake 53 on the rear driving axle of the vehicle.

45 At 54, (see Fig. 7) is denoted a projecting lug on the cam wheel 44, and the purpose of the same will now be described. The size of the cam wheel 44 or the ratio of its connection with the drive shaft of the 50 motor vehicle is such that one revolution of this wheel represents the proper interval between a pair of openings which are made by means of the drilling mechanism. When a hole has been made in the ground 55 by the drilling member 12 the operator of the vehicle moves the operating lever 50 on its pivot so as to engage the same on the lug 54 of the cam wheel and throwing in his clutch the vehicle will move forwardly 60 causing rotation of the cam wheel by reason of its connection with the vehicle drive shaft. When the wheel 44 has substantially rotated a single rotation, the lever moving around the groove 48 reaches the deep portion 65 of the groove 49 and under actuation

of the spring 51 applies the brake to the vehicle through the operative connection 52 and brings the vehicle to a stop automatically so that the hole drilled as just mentioned will be properly located at a predetermined distance from the hole last bored. 70

Having thus described the invention what I claim as new is:

1. In apparatus of the class described, the combination of a vehicle, means for propelling said vehicle, drilling mechanism carried thereby for drilling holes, means for automatically discontinuing movement of the vehicle to permit operation of the drilling mechanism, said propelling means being operable upon cessation of drilling action to 80 continue the vehicle movement. 75

2. In apparatus of the class described, the combination of a vehicle, drilling mechanism for boring holes, common means for propelling the vehicle and operating the drilling means, brake mechanism for said vehicle, and means for applying the brake at predetermined points in the movement 85 of said vehicle. 90

3. In apparatus of the class described, the combination of a vehicle, drilling mechanism for boring holes, means for propelling the vehicle and operating the drilling mechanism, a brake lever, and means co-operating with said brake lever to control the operation of the same upon movement 95 of said vehicle a predetermined distance. 95

4. In apparatus of the class described, the combination of a vehicle, drilling mechanism for boring holes, means for propelling the vehicle and operating the drilling mechanism, a brake lever, and means co-operating with said brake lever to control the operation of the same upon movement 100 of said vehicle a predetermined distance, 105 said means comprising a cam wheel operatively connected to the vehicle driving mechanism. 105

5. In apparatus of the class described, the combination of a vehicle, drilling mechanism for boring holes, means for propelling the vehicle and operating the drilling mechanism, a brake lever, means co-operating with said brake lever to control the operation of the same upon movement of said vehicle a predetermined distance, 110 said means comprising a cam wheel, and means for holding the lever in co-operative position 115 with respect to said wheel. 120

6. In apparatus of the class described, the combination of a vehicle, drilling mechanism for boring holes, means for propelling the vehicle and operating the drilling mechanism, a brake lever, means co-operating with said brake lever to control the operation of the same upon movement of said vehicle a predetermined distance, said means comprising a cam wheel formed with a 125 groove in which the brake lever is seated, 130

yieldable means for holding the lever in the groove, and means on said wheel for holding the lever out of coöperative relation with respect to the groove whereby to permit free movement of the vehicle.

7. In apparatus of the class described, the combination of a vehicle, a drilling mechanism for boring holes, means for propelling the vehicle and operating the drilling mechanism, a brake lever, and means coöperating with said brake lever to control the operation of the same upon movement of said vehicle a predetermined distance, said means comprising a cam wheel formed with a groove in which the brake lever is seated, yieldable means for holding the lever in the groove consisting of a spring, a projection formed on said wheel with which the lever is adapted to be engaged to release the vehicle brake, said lever being automatically disengaged from the projection upon rotation of the cam wheel whereby to permit application of the brake upon movement of the vehicle a predetermined distance.

8. In apparatus of the class described, the combination of a vehicle, drilling mechanism for boring holes, means for propelling the vehicle and operating the drilling mechanism, a brake lever, and means coöperating with said brake lever to control the operation of the same upon movement of said vehicle a predetermined distance, said means comprising a cam wheel having a predetermined ratio with respect to the driving means of the vehicle, and driving means whereby on a single rotation of the cam wheel the brake lever is actuated to stop movement of said vehicle.

9. In apparatus of the class described, the combination of a vehicle, propelling means for said vehicle, drilling mechanism for boring holes carried by said vehicle and comprising a hole boring tool, means for raising and lowering said tool, actuating means intermediate the vehicle propelling means and the tool for imparting rotation to the latter, and a clutch operatively connecting the actuating means with the tool whereby to rotate the latter during raising and lowering movements, said clutch including a relatively stationary element having spline connections with the tool and a rela-

tively movable element having free connection with the tool for longitudinal movement therealong.

10. In apparatus of the class described, the combination of a vehicle, propelling means for said vehicle, drilling mechanism for boring holes carried by said vehicle and comprising a hole boring tool, means for raising and lowering said tool, actuating means intermediate the vehicle propelling means and the tool for imparting rotation to the latter, and a clutch operatively connecting the actuating means with the tool whereby to rotate the latter during raising and lowering movements, said clutch including a relatively stationary element having spline connection with the tool, a relatively movable element having free connection with the tool for longitudinal movement therealong, and manipulating means for operating the clutch.

11. In apparatus of the class described, the combination of a vehicle, propelling means for said vehicle, drilling mechanism for boring holes carried by said vehicle and comprising a hole boring tool, means for raising and lowering said tool, actuating means intermediate the vehicle propelling means and the tool for imparting rotation to the latter, and a clutch operatively connecting the actuating means with the tool whereby to rotate the latter during raising and lowering movements, said clutch including a relatively stationary element having spline connection with the tool, and a relatively movable element having free connection with the tool for longitudinal movement therealong, and manipulating means for operating the clutch, said manipulating means comprising a lifting lever connected at one end to the relatively movable clutch element, and a shifting lever connected to the other end of the last mentioned lever for engaging and disengaging the clutch elements.

In testimony whereof I affix my signature in presence of two witnesses.

JAKOB V. GUDMOND-HÖYER.
